UNITED STATES PATENT OFFICE.

JOHN WILSON ORROCK, OF MONTREAL, QUEBEC, CANADA.

WEATHERPROOF RAIL STAND FOR TRACK SCALES.

Application filed May 1, 1923. Serial No. 635,962.

To all whom it may concern:

Be it known that I, JOHN WILSON ORROCK, citizen of the Dominion of Canada, residing at Montreal, in the Province of Quebec and Dominion of Canada, have invented certain new and useful Improvements in Weatherproof Rail Stands for Track Scales, of which the following is a specification.

10 This invention relates to improvements in weather covers for track scales, and more particularly to an improved stand for supporting the rails and ventilating the scale pit while preventing the ingress of water.

15 The freezing of drain water or water of condensation on the working parts of the scale mechanism is objectionable to the proper maintenance of track scales. Therefore, it is desirable to keep water from 20 draining into the pit as well as to provide the proper circulation of air to carry off moisture and to that end the constructions shown in my prior patents, 1,335,599, March 30, 1920, and 1,426,003, August 15, 1922, 25 were designed. In the construction of the former patent, the dead rails are supported directly on the deck of the pit, while the live rails are supported on the scale within the pit through the medium of rail stands 30 which project through openings in the deck. In the latter patent the dead rails are supported on rail stands which project through the openings in the deck, the rail stands being in turn mounted on a solid support independent of the deck, while the live rails 35 are supported on the scale in a manner similar to that disclosed in the former patent. In each construction, the rail stands which project through the openings in the deck are 40 each provided with a depending apron which overhangs a flashing secured to the deck, thus permitting the ventilation of the pit and at the same time preventing the ingress of water. The stand and the integral 45 apron above noted are formed of cast metal and consequently this construction prevents ready access for the insertion or manipulation of the rail clamping bolts. The clamping means for the rails include clamping plates and bolts, the latter because of 50 said inaccessibility, being passed upwardly through the head of the rail stand. This necessitates the locking nut being associated with the upper end of the bolt and conse-

quently this nut is exposed to the atmosphere which results in the corrosion of the parts. It is impracticable with this type to reverse the bolt so as to protect the nut from the weather because the integral depending apron which overlaps the flashing prevents sufficient access to the proper manipulation of the nut.

One of the principal objects of my invention is, therefore, to provide an apron which is detachably connected with the head of the rail stand, whereby said apron may be lowered into position around the flashing so as to permit ready access to the locking nut of the rail clamping means.

Another object of the invention is to provide a detachable apron which is adapted to be lifted vertically into position, and then rotated horizontally into interlocking engagement with the head of the rail stand, whereby the apron will be held against vertical movement.

A further object of the invention is to provide such an apron with means cooperating with the rail stand head to prevent lateral creeping of the apron and consequent displacement thereof.

A still further object of the invention is to provide an apron and also a flashing of sheet metal which will be cheaper to manufacture than the aprons and flashings heretofore employed.

Other objects of the invention will appear to those skilled in this art as the details of this improvement are more fully described, illustrated and claimed, and though the essential features of the improvement are necessarily susceptible of a wide range of structural modification, a preferred and practical embodiment is shown in the accompanying drawings, in which:—

Figure 1 is a staggered longitudinal sectional view showing the mounting of both the live and dead rail stands independently of the roof and the means for supporting the latter.

Figure 2 is a detail showing in cross-section the supports for both the live and dead rails, and also showing my improved apron and flashing.

Figure 3 is an enlarged vertical sectional view through one of the rail stands and deck.

Figure 4 is a view in elevation of one of

the rail stands, the apron being shown in a section to better disclose the supporting means therefor.

Figure 5 is a top plan view of one of the 5 rail stands.

Figure 6 is a detail sectional view showing the means for locking the apron against circumferential creeping.

Figure 7 is a perspective view of the 10 apron and

Figure 8 is a perspective view of the flashing.

In carrying out the invention, I provide the usual scale pit 5 and cover the same by 15 my arched deck 6, such, for instance, as is shown in my prior patent No. 1,426,003. The deck is supported independently of the live rails 7 and dead rails 8 by means of a series of beams 9. The dead rails are solidly 20 supported on a pit structure through the medium of an I-beam 10, and the live rails are supported on the scale (not shown) through the medium of metal supports 11. Both the I-beam or support 10 for the dead 25 rails, and the supports 11 for the live rails are disposed below the deck, and in order to support both the live rails and the dead rails in an elevated position above the deck and in such relation as to permit of the deck 30 draining the water outwardly to the sides and ends of the scale pit, I have provided a plurality of rail stands 12 and 13 for the respective live and dead rails. These stands project upwardly through openings 14 35 formed in the deck. Inasmuch as the rail stands, and the associated apron and flashing are identical, the description of one will suffice.

Each rail stand is preferably formed of 40 cast metal, and includes a circular base 15 and a circular head 16, the latter being concentric with the base, but having a considerably greater diameter. The diameter of the base 15 is considerably less than the diameter 45 of the opening 14 so as to provide a resultant air passage 17. The diameter of the head 16 is greater than the opening 14 so as to overlap the edges thereof. Connecting the head and base is a plurality of vertically disposed radial ribs 18. In the construction shown there are four of these ribs 18 arranged equi-distant apart. The base is provided with suitable openings for the insertion of attaching bolts whereby the rail stand may be secured to either a beam 10 50 or to a support 11.

The rail is seated upon the head 16 and is secured thereto by the clamping plates or 55 clips 19, bolts 20 passing downwardly through aligned openings 21 and 22 respectively formed in the plates 19 and the heads 16. On the lower end of each bolt is threaded a locking nut 23, said nut bearing against the under face of the head 16. The bolt openings 22 are disposed in close prox-

imity to the outer edges of the ribs 18, whereby the nuts 23 will engage said ribs and thus be prevented from turning. Each bolt is formed with an angular head which may be engaged by a tool for the purpose 79 of turning the bolt. By projecting the bolt downwardly and positioning the nut on the underside of the head 16, said nut and its threaded connection with the bolt is protected from the weather and consequently 75 corrosion of the parts is avoided.

In order to permit the pit being properly ventilated through the passage 17 and at the same time prevent the ingress of water into the pit through said passage, I have provided a flashing 24 and an apron 25 which are arranged in telescopic relation and are respectively carried by the deck 6 and the head 16 of the rail stand.

The flashing 24 is formed from a strip of 85 sheet metal and bent into circular formation, the meeting ends being interlocked as indicated at 24^a. The internal diameter of the flashing is substantially equal to the diameter of the corresponding opening 14 90 in the deck. The lower edge portion of the flashing is cut into a plurality of attaching sections 26, these sections being subsequently bent outwardly at right angles to form an attaching flange. Each section of this 95 flange is formed with an opening 27. The flashing is seated upon the planking of the deck 6 and is disposed in alignment with the corresponding opening 14. Nails are then driven through the openings 17 of the flange 100 sections 26 and into the deck planking so as to rigidly secure the flashing against movement. The weather-proofing material 6^a of the deck is then lapped over the flange sections 26 so as to create a water proof joint. 105

The apron 25 is likewise formed from a single strip of sheet metal and is bent into circular formation, the meeting ends being interlocked as at 25^a. The diameter of the apron is not only greater than the diameter 110 of the flashing 24, but is greater than the opening 14, thus providing an air passage 28 between the flashing and the apron. The upper edge of the apron 25 is adapted to be positioned in a downwardly extending 115 peripheral recess 29 formed in the head 16 of the rail stand. In order to support the apron against vertical movement, I have provided the head 16 of the rail stand adjacent the periphery thereof with a pair of diametrically opposed depending lugs 30-30 which are respectively formed with inwardly extending slots or seats 31 for receiving inwardly extending lugs 32-32 stamped from the body of the apron. In order to 120 prevent lateral creeping of the apron and consequent displacement thereof, due to the passage of cars along the rails, I have provided the apron with an inwardly extending lug 33 which is provided with a plurality 125

of openings 34. The lug 33 is adapted to be disposed directly against the lower surface of the head 16 and a locking pin 35 is passed through an opening in the head 16 and into any one of the openings 34 of said lug 33.

From the foregoing, it will be noted that I have provided a rail stand of a construction which will permit of uninterrupted drainage of the deck from the crown to the sides thereof; that the flashing and the apron serve to prevent the ingress of water into the scale pit and at the same time permit the pit to be properly ventilated, the air passing outwardly through the passages 17 and 28; that the apron may be positioned on the deck around the flashing prior to the securing of the rail fastening means to the head of the stand; and that after the rail fastening means have been properly positioned and secured the apron may be easily raised so that its upper edge will be disposed within the peripheral seat 29 of the head, the apron being then turned in a horizontal plane and interlocked with said head, after which the locking pin 35 will be seated to secure the apron against any lateral movement due to creeping caused by the passage of cars along the rails. It will also be observed that by means of the detachable connection between the apron and the head, I have provided means whereby ready access may be had to the rail fastening means either in assembling or in repairing the structure.

35 I claim:—

1. A weather proof rail stand for track scales including a flashing, a rail supporting stand projecting through said flashing and having a head provided with lug receiving seats, and an apron having offset lugs for engaging in said seats and depending from said head in overlapping relation to said flashing.

2. A weather proof rail stand for track scales including a flashing and a rail stand projecting through the same, said stand having a head provided with lug receiving seats, and a tubular apron having means for detachably engaging with said lug receiving seats thereby to suspend said apron from the head of the rail stand when attached to hold the same in overlapping relation to said flashing.

3. A weather proof rail stand comprising the stand having a head provided with lug receiving seats, and a tubular apron adapted to be disposed about the shank portion of the stand and having inwardly extending lugs adapted to engage and disengage said lug receiving seats upon the relative rotation of the apron with reference thereto.

4. A weather proof rail stand comprising the stand having a head, the head being formed with depending lugs respectively provided with inwardly extending lateral

slots forming seats, and a sheet metal apron surrounding the stand and formed with inwardly extending lugs engageable with said seats for detachably supporting said apron.

5. A weather proof rail stand comprising the stand having a circular head formed with a downwardly opening peripheral recess and with lugs depending below said recess, and a circular sheet metal apron having its upper end fitting the recess of said head and provided with means for detachably engaging the lugs of the head for supporting said apron.

6. A weather proof rail stand comprising the stand having a head, and a detachable apron rotatably movable into interlocking relation with said head whereby the apron will be supported against vertical movement relative to said stand.

7. A weather proof rail stand comprising the stand having a head, a detachable apron movable laterally into interlocking relation with said head whereby the apron will be supported against vertical movement relative to said stand, and means co-operating with said stand and head for preventing lateral creeping of said apron.

8. A weather proof rail stand comprising the stand having a head, a detachable apron movable laterally into interlocking relation with said head whereby the apron will be supported against vertical movement relative to said stand, and means co-operating with said stand and head for preventing lateral creeping of said apron, said means including an inwardly extending lug, and a removable locking element co-operating with the head and lug.

9. A weather proof rail stand comprising the stand, including a head, a base, and radially disposed connecting webs, of rail clamping plates supported on said heads, bolts extending downwardly through the respective clamping plates and head, and securing nuts threaded onto the lower ends of said bolts, said nuts being held against turning movement by engagement with the outer edges of the webs.

10. A weather proof rail stand construction including a head formed with a reduced portion providing an overhanging shoulder, and a tubular apron having its upper edge disposed in protecting relation beneath said shoulder and having means for detachably interlocking with said head.

11. A weather cover construction for track scales including the deck covering said pit and having openings therein, rail stands projecting upwardly through the respective openings of the deck, rails mounted on said rail stands, fastening means for the rails, engageable with said stands, and means associated with each rail stand for permitting ventilation of the pit and for preventing ingress of water into said pit, said means

comprising telescopically arranged flashing and apron surrounding the projecting part of the rail stand, the flashing having a water tight connection with the deck and the 5 apron having a detachable connection with the upper portion of the rail stand for permitting ready access to the rail fastening means.

12. A weather cover construction for track 10 scales including the deck covering said pit and having openings therein, rail stands projecting upwardly through the respective openings of the deck, each rail stand being formed with a head, rails supported on said 15 heads, clamping plates for the rails, bolts for the clamping plates passing downwardly through the heads of said rail stands, nuts engageable with the lower ends of said bolts,

and means associated with each rail stand 20 for permitting ventilation of the pit and for preventing ingress of water into said pit, said means comprising telescopically arranged flashing and apron surrounding the projecting part of the rail stand, the flashing having a water tight connection with the deck and the apron having a detachable connection with the upper portion of the rail stand, for permitting access to the nuts 25 of the rail clamping bolts.

In testimony whereof I hereunto affix my 30 signature in the presence of two witnesses.

JOHN WILSON ORROCK.

Witnesses:

IAN WARREN,
W. J. McALLISTER.
